UNITED STATES PATENT OFFICE.

CARL VOGEL, OF BERLIN-SCHONEBERG, GERMANY, ASSIGNOR TO WESTINGHOUSE ELECTRIC & MANUFACTURING COMPANY, A CORPORATION OF PENNSYLVANIA.

SWITCH MECHANISM.

Application filed March 31, 1925, Serial No. 19,627, and in Germany April 1, 1924.

My invention relates to actuating mechanism and particularly to mechanism for imparting a quick or snap action to an electrical switch.

5 One object of my invention is to provide an actuating mechanism for switches and apparatus requiring quick movements in opposite directions, that is simple in construction and which is adaptable particularly to snap 10 switches of the tumbler type.

Another object of my invention is to provide an actuating mechanism of the over-center type in which the pressure of the switch member in engagement with a contact member is maintained or actually increased until the instant the switch member is separated from the contact member with a snap action and during the time that the actuating mechanism is approaching the central position of its movement.

20 Another object of my invention is to provide an over-center actuating mechanism for an electric switch that is adaptable for use as a double-throw switch wherein there is no 25 central or neutral position, but wherein the switch member is yieldingly maintained in either of two operative positions.

These and other objects that will be made 30 apparent throughout the further description of my invention are attained by means 35 of the actuating mechanism hereinafter described and illustrated in the accompanying drawing, wherein the figure is an elevational view of actuating mechanism embodying features of my invention and shown applied to 40 a double throw switch.

Referring to the drawing, the actuating mechanism includes a supporting base 1 made 45 preferably of insulating material and upon 50 which a switch actuating cam 2 is pivotally mounted by means of a shaft 3. The cam comprises a disk having two arcuate surfaces 4 and 5 that are oppositely disposed and converge to points 6 and 7 at opposite ends of 55 the cam. A switch member 8, preferably 60 consisting of a flat bronze strip which may be flexed when pressed into engagement with contact members 9 and 10, is rigidly secured to the cam 2 and is so positioned that it alternately engages the contact members 9 and 10 when the cam member 2 is moved from the 65 position shown to its other operative position indicated by the dot-and-dash center line A.

The cam 2 is actuated by means of a pair 70 of operating arms 11 and 12 that are pivot-

ally attached to yoke members 13 and 14 respectively, which are adjustably secured to a rocking bar 15 that is pivoted to a stationary shaft 16. The yoke members 13 and 14 may be adjusted upon the bar 15 by turning 60 screws 17 and 18 respectively, for the purpose of varying the distance between the pivot points 19 and 20 and the shaft 16. The purpose of the adjustment will hereinafter be made apparent.

65 The free ends of the operating arms 11 and 12 are provided with rollers 21 and 22 respectively, that as indicated in the drawing normally engage opposite surfaces 4 and 5 of the cam member 2. The arms 11 and 12 70 are normally biased in engagement with the cam surfaces by means of a helical spring 23 that is pivotally connected between them. The bar 15 is provided with an operating handle 24 by means of which the bar may be 75 moved from the position shown in the drawing to a position indicated by the dot-and-dash center line B.

When the parts are in the position shown 80 in the drawing, the switch member 8 is yieldingly biased to engage the contact member 9. When it is desired to move the switch member into engagement with the switch contact 10, the rocking bar 15 is moved to the 85 position B which causes the rollers 21 and 22 to be moved into engagement with the opposite surfaces 5 and 4 respectively, of the cam member 2. As the rollers 21 and 22 are moved toward the pointed ends of the cam, the pressure of contact between the switch 90 member 8 and the contact member 9 is increased because of the increase in the lengths of the lever arms of the forces applied to the cam by the rollers as they approach the pointed ends thereof, and by reason of the increased tension of the spring 23 which is expanded as the operating arms are separated.

95 Because of the rollers 21 and 22 and the pointed ends of the cam member 2, there can be no stable central or neutral position and 100 consequently increasing pressure is applied between the switch member and the contact member 9 until the rollers pass over the points of the cam, at which time the spring 23 will contract and cause the rollers 21 and 22 to rotate the cam and thereby bring the switch member 8 into engagement with the contact member 10. By reason of the adjustments of the points of attachment of the operating arms with respect to the shaft 16, the arms 105 110

may be so adjusted that the rollers simultaneously engage the points on the cam and simultaneously act upon the opposite surface of the cam to cause it to change position with 5 a snap action.

It will be seen from the foregoing that the movement of the cam is entirely independent of the position of the operating handle 24 after the rollers have moved past the central 10 position. The hand of the operator therefore cannot interfere with the snap action of the switch.

The movement of the switch is limited by means of stop shoulders 25 and 26 on the base 15 member 1 that are engaged by an extension 27 secured to the cam. Movement of the free ends of the operating arms 11 and 12 is also limited by inclined surfaces 28 and 29 on the base member which are engaged by the rollers 20 21 and 22 respectively.

The construction is simple and inexpensive and is applicable to a variety of switch devices wherein snap action movement of the switch member is desired.

25 While I have described and illustrated several embodiments of my invention, it will be apparent to those skilled in the art that various changes, modifications, substitutions, omissions and additions may be made in the 30 apparatus illustrated without departing from the spirit and scope of my invention, as set forth in the appended claims.

I claim as my invention:

1. An over-center operating mechanism comprising a pivoted cam member having opposite cam surfaces converging toward opposite ends thereof, a rocking member, a pair of operating arms pivotally connected thereto and having their free ends yieldingly engaging opposite surfaces of the cam member for imparting movement thereto when the said operating members are moved into engagement respectively with the opposite cam surfaces and means for relatively adjusting the operating arms. 35

2. Switch mechanism comprising a pivoted cam member having opposite cam surfaces converging toward opposite ends thereof, a stationary contact member, a movable switch member connected to the cam member and movable thereby into and out of engagement with the contact member, a rocking member pivoted eccentric to the cam member, a pair of operating arms pivotally connected thereto and having their free ends yieldingly engaging opposite surfaces of the cam member for imparting movement thereto when the said operating members are moved into engagement respectively with the opposite cam surfaces. 40 50 55

In testimony whereof, I have hereunto subscribed my name this 12th day of March, 1925.

CARL VOGEL. 60
